Primary Examiner—Ralf T. Seifert**Attorney, Agent, or Firm**—Grace J. Fishel**[57] CLAIM**

The ornamental design for a bow harness, as shown and described.

DESCRIPTION

FIG. 1 is a front elevational view of a bow harness showing my new design;

FIG. 2 is a left side view thereof;

FIG. 3 is a rear elevational view thereof; and,

FIG. 4 is a top view thereof.

The interior of the vest is plain and unornamented.
